UNITED STATES PATENT OFFICE.

FREDERICK A. COLEMAN, OF CLEVELAND HEIGHTS, OHIO, ASSIGNOR TO THE FOUNDRY EQUIPMENT COMPANY, OF CLEVELAND, OHIO, A CORPORATION OF OHIO.

DRAWER-OPERATING MECHANISM.

1,274,141.

Specification of Letters Patent.

Patented July 30, 1918.

Application filed December 31, 1915. Serial No. 69,704.

To all whom it may concern:

Be it known that I, FREDERICK A. COLEMAN, a citizen of the United States, residing at Cleveland Heights village, in the county of Cuyahoga and State of Ohio, have invented a certain new and useful Improvement in Drawer-Operating Mechanism, of which the following is a full, clear, and exact description, reference being had to the accompanying drawings.

An object of this invention is to provide a simple efficient mechanism by which the weight of a drawer may be carried on rolling supports for purposes of moving the same inwardly and outwardly. Another object of the invention is to so arrange the rolling supports and the mechanism engaging the drawer that the drawer may be supported at widely separated points, thereby securely maintaining the drawer in its substantially horizontal position. Another object of the invention is to provide means whereby such a mechanism may be adapted to operate any one or more of a series of superimposed drawers. A more specific object is to provide a simple and conveniently operable means by which a selected drawer of a series may be attached to and operated by my mechanism.

My invention is hereinafter more fully described in connection with the accompanying drawings and the essential characteristics are set forth in the claims.

In the drawings Figure 1 is a front elevation of a core oven showing the series of drawers and my operating device in position in front of the same; Fig. 2 is a transverse vertical section through the series of drawers showing the operating device in side elevation and showing one of the drawers withdrawn to its outer position; Fig. 3 is a side elevation of the operating mechanism showing the same in position in front of the drawers before engaging them, the drawers being shown in section; Fig. 4 is a horizontal section through one of the drawers showing the adjacent parts of the operating mechanism in section; Fig. 5 is a detail of one of the devices for engaging a drawer, illustrating the selective feature.

While the drawings illustrate my invention as used with the drawers of a core oven, it is to be understood that it may be used with any drawer or series of superimposed drawers requiring such a mechanism.

Referring to the drawings by reference numerals, 1 and 2 indicate the side walls of a core oven, 3 the rear wall thereof, 4 a suitable top and 5 a front plate provided with a vertically arranged series of openings 60 through which the drawers may operate.

As shown the drawers comprise a bed plate 10 preferably a casting forming a grille work to permit the free passage of gas upwardly through the same for heating cores 65 or other articles carried thereby. The front 12 is securely carried by the bed plate and is shown as having outwardly extending flanges embracing the edges of a plate 13 of any suitable heat insulating material to 70 which the handles 14 are attached. At the rear of the bed plate is provided an upright plate 15 adapted to close the opening through which the drawer operates when the drawer is in its outer position, as illustrated in Fig. 75 2. Extending rearwardly from the plate 15 are brackets 16 having bearing surfaces 17 on their under sides adapted to engage and roll on horizontal shafts 20 rigid with flanged wheels 22, which in turn engage and roll 80 on rails 24 extending from the front plate 5 to the rear wall 3. These rails are preferably in the form of angle irons carried at their inner ends on angle irons 25 and at their outer or forward ends on inwardly 85 projecting flanges 26, shown as integral with the front plate 5. The length of the bearing surface 17 is such that the shaft may travel from a downwardly curved portion at its inner end to a shoulder at its forward 90 end without sliding on the same, such travel being due to the turning of the flanged wheels 22 as they travel along the rails 24 the distance required to move the drawers from the outer to the inner position. 95

While being moved and while in their outer position, the forward ends of the drawers are supported by the operating mechanism which carries the forward end of the drawer slightly above its normal height so 100 that the under side of the base 10 is free from the lower edge of the opening in the front plate, occupied by the drawers. The operating mechanism for engaging the front of the drawer and by which it may be moved 105 will now be described.

A suitable trackway is provided above the series of drawers, which is shown as comprising a pair of channel irons 30 resting on top of the top wall 4 and securely an- 110

ched at their rear ends by a cross member 32 and anchoring bolts 34 secured thereto and extending downwardly and anchored within the rear wall 3. In the core oven 5 shown in the drawings this rear wall is preferably made up of suitable masonry to which the bolts 34 may be anchored as shown. The track members or rails 30 project forwardly over the drawers, as shown in Fig. 10 2, and are adapted to carry a suitable trolley 35 shown as comprising a suitable frame 36 mounted on two pair of flanged wheels 37 and 38, the flanges of which engage the inner sides of the channels, as shown in 15 Fig. 1. The forward ends of the channels 30 may be braced by each other or by a suitable cross member 40 shown as an angle iron extending across the tops of the same and secured thereto. This member 40 serves as 20 a stop to prevent the trolley running off of the ends of its rails by engaging the wheels 38 when the trolley reaches the end of its forward movement.

The means by which the front ends of the 25 drawers are raised and supported by trolley 35 will now be described.

Depending from the frame 36 are two vertical members shown as angle irons 44, each braced by a plate shown at 46. The 30 angle irons 44 are each so positioned that one flange turns toward the drawer, and to these flanges are pivoted a series of hooks 47 shown as having bifurcated portions extending over the sides of the flanges and engaging pivot pins 48. The free ends of these hooks are provided with upwardly turned portions 49 forming the hook proper which is adapted to engage the downwardly opening recess formed by the handle members 14. 35

40 The means for raising these hooks for engaging the handles of the drawers comprise two pair of parallel vertical rods depending from the short arm of the levers 50 pivoted on a shaft 51 carried by the frame 36 of the trolley, and each pair of these rods designated 52 extends downwardly each side of a vertical row of the hooks 47. Below each of these hooks is provided a pivoted distance block 53 carried on a rock shaft 54 extending through the rods 52 and having a handle 56 at each end by which the distance blocks on the shaft may be swung upwardly. This movement brings the rounded free end of each block into engagement with a notch 57 in the lower side of the associated hook member 47. When the distance piece is in this position the hook member is supported in its horizontal position, while in its normal position the block 55 is swung downwardly, as shown in Figs. 2 and 3, until the shoulder between the bifurcated portion engages the edge of the flange of the angle iron to which the hook is pivoted, permitting the hook to stand below its 60 engaging position. Now when two of these 65

hooks have been swung upwardly to their horizontal position by the distance blocks 53, the hooks standing beneath the handles 14 of the drawer, the rods 52 are raised by swinging the levers 50 which carry downwardly extending links 60 connected to short rock arms 62 rigid on a rock shaft 63. This shaft is carried in suitable brackets supported on the angle iron members 44 and is adapted to be operated by a hand lever 64 75 shown as provided with a suitable handle 65. A more complete description of the operation is as follows:

The hand levers 56 opposite the drawer desired to be operated are moved from their depending position, shown in Fig. 3, to the position shown in Fig. 5, raising the distance blocks and bringing the hook members 47 into position to engage the projecting handles 14 on the drawer to be withdrawn. 80 The lever 64 is then swung downwardly from the position shown in Fig. 3 to the position shown in Fig. 2, acting through the links 60, the levers 50 and rods 52 to raise the hooks and thereby raising the front end 90 of the drawer free from the opening in the front plate 5, through which the drawer operates. The drawer is then supported on four points, by the two separated hooks 47 and the two brackets 16 on the roller device 95 comprising the shaft 20 and the wheels 22. Thus the drawer is very stable and not affected by a greater weight on one edge than on the other.

As the handle 64 is swung downwardly 100 the rock arms 62 bring the lower ends of the links 60 inwardly to such a point that the direction of pull is within the axis (toward the drawers) of the rock shaft 63, as will be seen from Fig. 2. Thus the downward pull on the rods 52 acting through the lever 50 and link 60 tends to bring the rock arms 62 against the angle bars 44 and hold the lever 64 in the position shown in Fig. 2, 105 obviating the necessity of manually holding the lever in this position. Following the downward movement of the lever 64 it is only necessary to draw forwardly on this lever to move the trolley 35 forwardly, and by reason of the engagement of the hooks 47 with the drawer handles the drawer follows and is withdrawn to the position shown in Fig. 2, where the upright plate 15 at the inner end closes the opening through which the drawer operates, preventing the escape 110 of hot gases. A reverse of this series of movements may serve to return the drawer to its innermost position, and the raising of the lever 64 may lower the front end of the drawer until it rests upon the adjacent portion of the front plate 5.

It is obvious that the others of the series of superimposed drawers may be withdrawn in a similar manner, it being only necessary to select the proper drawer by operating the 115

corresponding handle 56 and hooks 47, there being a pair of these hooks for each of the drawers.

From the foregoing description it will be seen that I have provided an apparatus by which any of a series of drawers may be withdrawn while supporting them in the most stable manner upon roller devices at the front and rear of the drawer, and while I have shown and described my invention as embodied in the drawers of a core furnace it is to be understood that I do not wish to limit my invention to this particular embodiment, for it is equally well adapted for many other purposes where the drawers are of such weight or size as to make desirable a mechanical operating means for withdrawing and moving the same into position.

Having thus described my invention, what I claim is:

1. The combination of a plurality of superimposed drawers, a trolley, mechanism carried thereby for engaging the drawers adjacent to their front ends, said mechanism having laterally spaced engaging devices adapted to support the drawer at two points, and a device common to both supporting members for operating them together.

2. The combination of a plurality of superimposed drawers, a trolley trackway extending longitudinally of the drawers, a trolley on the trackway, a pair of upright supporting bars carried by the trolley, means for engaging the various drawers carried by said supporting bars whereby said devices are in pairs for the various drawers, and a series of cross rods carried by said supporting bars, each cross rod being provided with means for operating both drawer engaging members appertaining thereto.

3. In a device of the character described, the combination, with a case, of a set of superimposed drawers therein, a set of movable hooks arranged in two tiers side by side, one pair of hooks for each drawer, a set of locking devices adapted to position any pair of hooks as a unit to engage the corresponding drawer, and a trolley carrying said sets of hooks and locking devices and adapted to carry them away from said case with the engaged drawer supported at two points at the front.

4. In a device of the character described, the combination with a series of superimposed drawers, a trackway extending forwardly from the drawers, a car movable on the trackway, an upright carried by the car in front of the drawers, selective devices carried by the upright and adapted to engage the series of drawers respectively, each selective device comprising a hook and means adapted to hold it in engaging posi-

tion, and connected lever and link mechanism carried by the car for raising any active hook.

5. In a device of the character described, the combination with a series of superimposed drawers, a trackway extending forwardly from the drawers, a car movable on the trackway, an upright carried by the car in front of the drawers, a series of selective devices carried by the upright and adapted to engage the series of drawers respectively, each selective device comprising a hook pivoted to the upright and a distance block adapted to be brought under such hook into engaging position, and means for bodily raising the series of distance blocks to raise the active hook.

6. In a device of the character described, the combination of a plurality of superimposed drawers, a plurality of pivoted hooks, one for each drawer, a plurality of distance blocks adapted to respectively position the hooks to engage the drawers, and mechanism for concurrently moving the various distance blocks.

7. The combination, with a plurality of superimposed drawers, of a withdrawing device having a support, a series of hooks pivoted thereto, a series of devices adapted to hold the hooks respectively in engagement with corresponding drawers, an upright member adapted to act simultaneously on the various devices mentioned, and means for moving the upright member vertically.

8. In a device of the character described, the combination of a plurality of superimposed drawers, an upright member, a series of hooks pivoted to the upright member and adapted to engage the respective drawers, a second upright member, a series of distance blocks pivoted to the last mentioned upright member and adapted to be turned to hold the hooks respectively in position to engage the drawers, and means for raising said second upright member.

9. In a device of the character described, the combination of a plurality of superimposed drawers, a supporting member adjacent to the front thereof, a set of hooks pivoted to such member and adapted to engage the drawers respectively, a movable upright bar, a series of distance blocks pivoted to such bar and each adapted to hold the corresponding hooks in a drawer-engaging position, an operating device, and connecting mechanism between the same and said bar for simultaneously operating the hook-locking devices.

10. In a device of the character described, the combination of a plurality of superimposed drawers, an upright adjacent to the front thereof, a set of hooks pivoted to the upright adapted to engage the drawers, a second upright member, a set of distance blocks carried by said second upright mem-

ber, and adapted to hold the respective hooks in a drawer-engaging position, a device movable in a direction parallel with the movement of the drawers and carrying the two upright members mentioned, and means for operating the upright member which carries the hook-locking devices.

11. In a device of the character described, the combination with a plurality of superimposed drawers, of a trackway running parallel with the direction of movement of said drawers, a car movable on said trackway, a supporting member carried by said car, a series of hooks carried by said member and adapted to coact with the respective drawers, a movable upright carried by the car, a set of locking devices carried by said upright adapted to hold the hooks in drawer-engaging position, an operating lever carried by the supporting member, and connecting mechanism between the same and the said upright to enable any drawer to be engaged and withdrawn.

12. In a device of the character described, the combination of a plurality of superimposed drawers, a trackway running parallel with the direction of movement of the drawers, a car movable on the trackway, an upright member carried by the car, a series of hooks each pivoted to said upright member, a pair of upright bars, horizontal shafts carried by such pair of bars, distance blocks respectively secured to the shafts between the bars of said pair and adapted to engage the under side of the respective hooks which extend between the bars of such pair, means for turning such shafts to bring the blocks to active or idle position, and mechanism

mounted on the car and adapted to raise said pair of bars.

13. In a device of the character described, the combination of a plurality of superimposed drawers, an elevated trackway running parallel with the direction of movement of the drawers, a car movable on the trackway, an upright member depending from the car, a series of hooks each pivoted to said upright member, an upright bar, distance blocks pivotally mounted on said bar and adapted to engage the under side of the respective hooks, means for turning such blocks to bring them to active or idle position, a lever pivotally mounted on the car and to which said bar is connected, and operating mechanism carried by said upright member and connected to the lever at another point.

14. In a device of the character described, the combination with a plurality of superimposed drawers, of a trackway running parallel with the direction of movement of said drawers, a car movable on said trackway, upright members carried by the car, hooks pivoted on said members for engaging each of the drawers, and longitudinally movable upright members carrying means for raising said hooks, the latter means comprising a pivoted distance block for each hook and a manually operable means for raising each block to bring the hook into engaging position, whereby such drawer may be supported by the car and moved therewith.

In testimony whereof, I hereunto affix my signature.

FREDERICK A. COLEMAN.
